INTERNAL-COMBUSTION ENGINE

Wilhelm B. Bronander, Montclair, N. J.

Application October 14, 1944, Serial No. 558,627

3 Claims. (Cl. 123—177)

This invention relates to internal combustion engines.

More particularly stated, the invention relates to valve mechanism for such engines.

In internal combustion engines, and particularly in aircraft engines, which are operated under high compression and at high speed, tremendous amounts of heat are developed. This has resulted in burning out the oil or lubricant which lubricates the exhaust valve stems, thereby causing the valves to freeze.

This invention has for its salient object to provide means for cooling the valve stem guides or bushings, thereby eliminating freezing of the valves.

Further objects of the invention will appear from the following specification taken in connection with the drawing which forms a part of this application, and in which there is shown a sectional elevation through a portion of the head of the engine illustrating valve mechanism embodying the invention.

In the particular embodiment of the invention illustrated, there is shown a portion 10 of the head of an engine having mounted therein a valve guide 11 in which is reciprocatably mounted a valve stem 12. The single valve stem as shown is hollow and has two outwardly flared portions 13 and 14 at the lower end of said single stem. A cap 15 is secured, as by welding shown at 16, to the flared portion 13. The cap 15 forms the valve head which seats against the valve seat 17 and, furthermore, has an inwardly extending conical portion 18 at the center thereof. Openings 19 are formed in the tapered portion 14 at the lower end thereof and circular openings 20 are formed in the upper portion of the wall of the tapered portion 14. The conical portion 18 promotes the circulation of the cooling medium in the valve cap and directs the medium laterally through the openings 19.

The portion 14, which may be carried by the stem or by the head or cap, may be tapered as shown or may have any other desired shape or configuration, and forms a support for the cap 15 to prevent buckling or collapsing of the cap. Thus the cap can be made much lighter, reducing the weight of the valve.

The upper end of the valve stem 12 has a central filling opening 25 which is normally closed by a pin 26 having a head 27. The head 27 forms the central portion of the flanged upper end 28

of the stem with which springs 29 of the usual construction cooperate to close the valve. The valve is operated in its opening movement by a rocker arm 30.

5 The hollow portion of the valve stem 12 is partially filled with a suitable cooling medium, such as sodium or suitable salts. By reason of the particular construction of the valve cap and flared portions of the lower end of the valve stem, the cooling medium is forced laterally through the openings 19 and "sloshes" back and forth in the valve stem, thus materially assisting in the cooling of the valve.

10 The cap 15 is preferably formed of Nichrome metal which is highly resistant to heat and is welded at 16 to the flared portion 13 of the valve stem, which is preferably formed of some material such as stainless steel.

15 Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

20 1. Valve structure comprising a hollow valve stem having a filling opening at one end and a hollow valve at the other end, and a plug for closing the filling opening forming a closed chamber in the valve, said valve having an inwardly extending conical portion at the center thereof and an outwardly flared internal wall forming a support for the valve head and provided with openings to facilitate circulation of the cooling medium in the hollow valve and stem.

25 2. Valve structure comprising a single thickness, closed, hollow valve stem and a hollow valve head carried by the stem, and bracing and supporting means in the head extending from the stem to the valve head to prevent buckling or collapsing of the valve head.

30 3. Valve structure comprising a single thickness, closed, hollow valve stem having a flared extension, a hollow valve head secured to the extension of the stem, and bracing and supporting means extending from the stem to the valve head to prevent buckling or collapsing of the valve head.

WILHELM B. BRONANDER.
